UNITED STATES PATENT OFFICE

LOUIS HERMANNI, OF PLEASANTON, NEBRASKA

HOG HOLDER

Application filed May 1, 1929. Serial No. 359,609.

The present invention relates to an apparatus for holding hogs and has for its prime object to provide means for efficiently and effectively holding a hog for the purpose of 5 castration, vaccination, and other similar operations.

Another very important object of the invention resides in the provision of an apparatus of this nature which is adapted to hold 10 in place different sized hogs.

A still further very important object of the invention resides in the provision of an apparatus of this nature which is exceedingly simple in its construction, inexpensive to manufacture, strong and durable, reliable in use, and otherwise well adapted to the purpose for 15 which it is designed.

With the above and numerous other objects in view as will appear as the description proceeds, the invention resides in certain novel features of construction, and in the combination and arrangement of parts as will be hereinafter more fully described and claimed.

In the drawing:

25 Figure 1 is a side elevation of the apparatus embodying the features of my invention,

Figure 2 is another side elevation thereof opposite to that shown in Figure 1 with the 30 lower portion broken away,

Figure 3 is a vertical transverse section therethrough,

Figure 4 is a perspective view of the adjustable bar, and

35 Figure 5 is a transverse vertical sectional view of the invention taken through an intermediate portion of the same.

Referring to the drawing in detail it will be seen that numerals 5 denote two pairs of 40 cross legs for supporting between their upper ends, the ends of a V-shaped trough T comprising sides 6 and 7. The lower ends of the pairs of legs are connected by bars 8 forming braces.

45 Bars 9 rise from intermediate portions of one brace 8 to the upper edge of the board 6 and are disposed in spaced parallelism and each is provided with a series of spaced pins 10.

50 Bracket arms 12 extend outwardly from

the board 7 and support a bar 14 and sleeves 15 and 16 having respectively loops 17 and 18 are mounted for longitudinally sliding movement on the bar. A strap 19 is fixed to the loop 17. A strap 20 is fixed to the board 7. 55

A leg engaging strap 21 is fixed to the loop 18 and is adjustable by means of buckles 22. A bar 23 has notched ends 24 for engaging pins 10 and is provided with an opening 25 to receive strap 20 and with an elongated slot 26 60 in which is slid able a bracket 27 having a loop 28 with which the strap 19 is engageable. The straps 19 and 20 are provided respectively with buckles 30 and 31 so that the straps may be adjusted. 65

A set screw 32 holds the bracket 27 in the desired adjusted position. Set screws 33 and 34 and sleeves 15 and 16 respectively hold these screws in adjusted position. Thus it will be seen that the leg strap may be moved 70 or adjusted longitudinally of the trough and the strap 19 may be adjusted longitudinally of the trough toward or away from the strap 20.

The bar 23 will be engaged with the pins 10 75 in accord with the size of the hog lying in the trough. It will thus be seen that a hog may be tightly held in place for castration, vaccination and other operations whereby said operation may be performed without danger 80 of injuring or harming the hog due to the effort of the animal to escape.

It is thought that the construction, utility and advantages of this invention will now be quite apparent to those skilled in this art 85 without a more detailed description thereof.

The present embodiment of the invention has been disclosed in considerable detail merely for the purposes of exemplification 90 since in actual practice it attains the features of advantage enumerated as desirable in the statement of the invention and the above description.

It is apparent that changes in the details 95 of construction, in the combination and arrangement of parts may be resorted to without departing from the spirit or scope of the invention as hereinafter claimed or sacrificing any of its advantages.

Having thus described my invention, what I claim as new is:

1. An apparatus of the class described comprising two pairs of cross legs, a V-shaped trough having its ends supported between the upper ends of the two pairs of cross legs, brackets on one side of the trough, a bar supported in said brackets, a sleeve slideable on said bar, means for holding the sleeve in adjusted position, a strap engaged with said sleeve, a pair of uprights on the other side of the trough each having a plurality of pins, a bar engageable with the pins, and having adjustable means connecting said strap thereto.
2. An apparatus of the class described comprising two pairs of cross legs, a V-shaped trough having its ends supported between the upper ends of the two pairs of cross legs, brackets on one side of the trough, a bar supported in said brackets, a sleeve slideable on said bar, means for holding the sleeve in adjusted position, a strap engaged with said sleeve, a pair of uprights on the other side of the trough each having a plurality of pins, a bar engageable with the pins, and having adjustable means connecting said strap thereto, another strap fixed to the first side of said trough and engaged with said second bar.
3. An apparatus of the class described comprising two pairs of cross legs, a V-shaped trough having its ends supported between the upper ends of the two pairs of cross legs, brackets on one side of the trough, a bar supported in said brackets, a sleeve slideable on said bar, means for holding the sleeve in adjusted position, a strap engaged with said sleeve, a pair of uprights on the other side of the trough each having a plurality of pins, a bar engageable with the pins, and having adjustable means connecting said strap thereto, another strap fixed to the first side of said trough and engaged with said second bar, a second sleeve slideable on the first bar, means for holding said second sleeve in adjusted position, and a leg strap engaged therewith.
4. An apparatus of the class described comprising two pairs of cross legs, a V-shaped trough having its ends supported between the upper ends of the two pairs of cross legs, brackets on one side of the trough, a bar supported in said brackets, a sleeve slideable on said bar, a set screw threaded through the sleeve for frictionally engaging the bar for holding the sleeve in adjusted position, a strap engaged with said sleeve, a pair of uprights on the other side of the trough each having a plurality of headed pins, a bar engageable with the pins having notched end portions for the reception of said pins, and having adjustable means connecting said strap thereto, another strap fixed to the first side of said trough and engaged with said second bar, a second sleeve slideable on the first bar, means

for holding said second sleeve in adjusted position, and a leg strap engaged therewith, all of said straps having buckles for adjustment purposes.

In testimony whereof I affix my signature.

LOUIS HERMANNI.
